UNITED STATES PATENT OFFICE

CHARLES F. LINDH, OF BROOKLYN, NEW YORK, ASSIGNOR TO STANDARD TOBACCO
STEMMER COMPANY, A CORPORATION OF VIRGINIA

LEAF-STEMMING DEVICE

Application filed May 9, 1928. Serial No. 276,297.

This invention relates to leaf-stemming devices, particularly for removing the stem or mid-rib from tobacco leaves as a preliminary operation to the manufacture of smoking or chewing tobacco, the present device being intended for manual operation. The main object of the present invention is to provide an apparatus for this purpose which will be convenient and rapid in operation. Another object is to provide a machine which is simple and convenient to operate, in which one handle may be operated to actuate a single one or a plurality of devices at will, in accordance with the pressure applied to the handle.

In the accompanying drawings:

Fig. 1 is a side elevation of the device, with a stem inserted;

Fig. 2 is a front elevation of the same;

Fig. 3 is a plan view of the device shown in Fig. 1;

Fig. 4 is a side elevation showing the lever in depressed position with the knife notches opened and the wiping pad raised into cleaning position, the dotted lines showing the closed position after the hand is removed; and

Fig. 5 is a front elevation showing the operation of the device, the two halves of a tobacco leaf being partly stripped off the stem.

In carrying the invention into effect, there is provided a pair of knives coacting to engage the stem of the leaf between them, together with means to separate the knives and a wiper to wipe the knives and mechanism for actuating the knife separating means and the wiper to first separate and then wipe said knives. In the best constructions, this mechanism includes two parts movable relative to each other to actuate the wiper and has a unit to actuate the separating means and a spring resisting said unitary movement and a stronger spring resisting the relative movement. In the best constructions also, there is provided a lever supporting one of the knives, which is manually operable to separate the knives, and means yieldingly pressing the knives together.

Referring to the drawings, a stand 6, which is intended to be permanently fastened to a

table or work-bench, has a lever 7 pivoted on a cap screw 8, the lever being held at a rest position on stop pin 9 by means of the weak tension spring 10 which is stretched between a pin 11 of lever 7 and one of several pins 12 inserted into the stand 6 for ready adjustment of the tension. A disc-shaped knife 13 is attached by means of a screw 14 to the stand 6, while another disc-shaped knife 15 is fastened by a screw 16 to the lever 7. These knives are provided with suitable sharpened notches around their circumferences and are mounted, by means of pins 17 and 18, inserted in stand 6 and lever 7 which engage unused notches of the knives at such positions that one of the notches of one knife registers with a notch of the other. To clean the notches, the lever 19 carried by the knife supporting lever 7 is pivoted on stud 20 and has, at its free end, a felt pad 2 which is preferably kept moist in any suitable way, positioned to wipe the knives. The compression spring 22, which is considerably stronger than spring 10, is placed in recesses provided for this purpose in the forward ends of the levers 7 and 19, and keeps the latter in its normal position with the pad out of engagement with the notched portion of the knives.

Adjacent to the registering notches, the stand 6 and the lever 7 are cut away so as to clear the notches, and the upper edges of the remaining portions are shaped to form the converging guideways 23 and 24 leading to the registering notches. After pressing the handle portion of lever 19 lightly to move lever 7 to separate the knives, the stem is inserted by pushing its butt-end down between these guideways into the knife notches. Releasing the lever 19 closes the notches over the stem and the leaf is stripped by pulling the stem transversely through said notches in the direction of the arrow shown in Fig. 5, with the right hand, while the left, after having guided the leaf part way into the notches, is free to pick up another leaf. Before gripping the butt of the next leaf preparatory to inserting it in the device with the right hand, the operator actuates the handle of lever 19 downwardly with the result, since spring 10 is made weaker than spring 22, that the levers 100

7 and 19 are first moved as a unit until lever 7 is arrested by stop pin 25, and then the lever 19 is moved relatively to the lever 7, causing the wiping pad to pass across the cutting notches, thus cleaning from the edges of the notches the gum from the leaf and any scraps left from the last stemming and held to the blades by said gum.

It will be seen that operation of one hand lever 19 serves to actuate lever 7, to separate the knives and in addition serves to actuate the cleaning device 21, or not, depending on whether a firm pressure or light pressure is given to said hand lever. By this arrangement the knives are necessarily separated to open the notched portions before the wiping action of the felt pad, whereby the scraps left in the notches may be more readily wiped out through the space between the knives.

23. The cutting edges of the knives sever the two halves of the leaf from the stem and, as long as the edges remain sharp, make a clean cut without injuring the leaf. After one set of notches has worn too dull to make a neat cut, the next set is put into action by loosening screws 14 and 16, and turning both discs by one notch, the pins 17 and 18 serving to automatically secure their registration with one another. After all the notches have been used in this manner, the worn knife discs are replaced by a new set, and the old discs are resharpened for future use.

What is claimed is:

1. In a leaf-stemming device, the combination with a pair of separable knives coacting to engage the stem between them, of a wiper to wipe the knives and means operating to first separate said knives and then actuate said wiper.

40. 2. In a leaf-stemming device, the combination with a pair of separable knives coacting to engage the stem between them, of a wiper to wipe the knives and means operating to first separate said knives and then actuate said wiper, said means including two parts movable relatively to each other to actuate the wiper and as a unit to separate the knives, a spring resisting said unitary movement and a stronger spring resisting said relative movement.

55. 3. In a leaf-stemming device, the combination with a pair of knives coacting to engage the stem between them, of a lever supporting one of said knives and manually operable to separate the knives, means yieldingly pressing the knives together, a cleaning device for cleaning the knives, and common means for manually operating said lever and said cleaning device.

60. 4. In a leaf-stemming device, the combination with a pair of knives coacting to engage the stem between them, of a lever supporting one of said knives and manually operable to separate the knives, means yieldingly pressing the knives together, a hand

lever pivoted on the knife supporting lever, means to cause movement of the levers as a unit followed by relative movement of the levers on actuation of the hand lever alone, and a cleaning device for cleaning the knives carried by said hand lever.

5. In a leaf-stemming device, the combination with a pair of knives coacting to engage the stem between them, of a lever supporting one of said knives and manually operable to separate the knives, and means yieldingly pressing the knives together, said knives being provided with a series of notches and means permitting positioning of the knives to locate any one of the notches in stem engaging position.

6. In a leaf-stemming device, in the combination with a pair of knives coacting to engage the stem between them, of means for separating the knives, means for cleaning the knives, a handle and mechanism actuated by said handle for operating at will the separating means alone, or both of said means.

In testimony whereof, I have signed my name to this specification:

CHARLES F. LINDH.
